UNITED STATES PATENT OFFICE

JULIUS C. HOCHMAN, OF NEW YORK, N. Y.

RELEASEABLE SCREW MECHANISM

Application filed January 30, 1922, Serial No. 532,571. Renewed September 6, 1928.

My present invention is shown as embodied in a variety of releasable locking-screw mechanisms. As my primary illustrative disclosure, I show it embodied in a monkey wrench for controlling the locking and releasing of the jaw-locking screw element or "worm", now commonly employed for hand adjustment. It will be obvious, however, that the same mechanism may be used wherever such a screw lock and release is desired; also that certain of its broadly novel principles and features may be embodied in other devices where it is desired for the operation or control of any screw-actuated, screw loaded, or screw-locked member, for automatic lock or automatic release thereof, and particularly for quick sliding adjustments with automatic screw-lock and -release.

In applying the invention to a monkey wrench I have found it possible and highly desirable to retain the ordinary screwing adjustability, as well as the outward appearance, structure and proportioning popularly recognized as characteristic of a monkey wrench; including the fixed jaw and a shank on which the sliding jaw slides, said shank having the usual rack and said sliding jaw having associated with it the adjusting worm or nut which co-operates with the rack; and, while preserving these within limits, I associate them with other mechanisms including a pilot screw element whereby the locking screw element may be automatically rotated to permit free sliding movements of the movable jaw in one or the other or both directions, as may be desired; these elements being organized for the purpose and with the result that the sliding jaw may be arranged to open or to close in response to endwise pressures, or to be automatically locked against said pressures in either desired one of said directions. Preferably, also there is an element, preferably a spring, whereby the sliding jaw is pressed toward the fixed jaw, preferably with sufficient power to give automatic closing of the jaws, though it may be mere balancing of the weight and friction of the sliding jaw; and in other embodiments I may utilize gravity in place of a spring, either as a balance or as a counter-balance.

In the monkey wrench the rotary locking screw element, the longitudinal rack to which it is threaded, the sliding jaw and the pilot screw element are all so organized that a slight angular movement of the handle of the monkey wrench when applying pressure to screw a nut or bolt in the desired direction, will operate to throw the parts into locking relation, while reversed pressure on the handle will release the locking element and put the pilot screw element in the automatic screwing relation to said locking element, preferably by imparting slight endwise movement to the pilot screw element. The locking direction for the pressure is preferably reversible by a simple adjustment; and in both directions, the locking movement brings the handle into solid contact with the shank, thereby relieving its pivotal centre of all strain.

Thus by my invention the monkey wrench becomes capable of operation as an automatic ratchet wrench, the jaws of which will open freely to rotate around the corners of a nut when pressure is applied to the handle in one direction, will close automatically, and will be automatically locked when pressure is applied to the handle in the opposite direction. Similarly the sliding jaw will slide open under hand pressure for application to the nut or bolt, when the handle is in the first position, and will automatically close, and will lock when the handle shifts under the reverse pressure.

For these purposes, the pitch and areas of the locking screw threads and other thrust-bearing surfaces of the rotating element are such as to afford prohibitive frictional opposition to any automatic screwing in response to the endwise thrusts or pressures applied either to said sliding jaw through said locking thread or to said locking thread through said sliding jaw; and the pilot screw element engaging the locking screw element is of the same pitch as the locking screw thread but on a radius so much smaller that the pitch angle of pilot thread is a slipping angle, preferably an angle of very easy slip. By slight endwise displacement of either one of the screw elements in the direction of an end-

wise applied thrust, the endwise load may be shifted from one screw element to the other with resultant endwise slip or endwise lock, according to which thread is caused to take the load. A very simple machine element such as a cam or lever may be employed to cause the required endwise shift and the operation of such machine element may be controlled manually or automatically in a great variety of ways. In the monkey wrench, the shift of load occurs just after the instant of substantially no-load when the pressure on the handle is reversed; so that when the new (reverse-screwing) load comes, the slip-screw will support only the very small pressure necessary to rotate the then unloaded worm through the very small angle necessary to free its locking screw threads from locking engagement with the rack. After this happens only endwise movement of the sliding jaw can cause any further rotation of the worm and such endwise movement can rotate the worm only at the exact speed required to keep its locking threads out of contact with the rack, because the pitch of the locking threads and the slip threads is precisely the same. Hence the only load that can ever come on the pilot screw is the free worm's frictional resistance to rotation and this resistance may be made practically negligible. Hence the pilot screw may be very light. With these basic elements, it is possible to combine many specifically different means for relative movement of the pilot screw with reference to the locking screw whereby the threads of the latter may be slightly rotated or otherwise moved out of locking frictional contact with the rack teeth or other relative stationary locking rack or screw element. The essential is that the worm becomes free for rotation and worming along the rack during, and because of, and at the rate compelled by the worm's endwise movement along the slip angle groove of said pilot screw element. The release of the frictional lock may be complete or partial as may be desired and the degree of frictional contact may be held absolutely constant for any period of time. Considered more specifically in some respects, and in others more broadly, my invention may be viewed as including a lock screw element having co-axial threaded relation with two other screw elements having the same number of turns per unit length but different pitch diameters, such that the engagement between the threads of greater diameter is either at a non-slip angle, or in any event at an angle which, with the other resistances, will afford a lock against endwise screwing in response to endwise pressure, while the engagement of the threads of lesser diameter is at a slip angle; in combination with means for causing or permitting shift of one or more of the screw elements, to bring the two sets of threads into and out of precise

"phase" or longitudinal registry, whereby the locking angle thread will take the load and will control when said elements are slightly de-phased in one direction or the other, and whereby, when said elements are precisely in phase, the slip angle thread will translate the load thrust into desired relative movements of certain of the parts. For most purposes it is desirable to have the clearance, or looseness of fit for the larger-diameter, locking-angle threads, greater than for the smaller-diameter, slip-angle threads. It is conceivable that for some purposes this relation of clearances might be reversed. Such reversal would be useful with reference to the broad novelty of my combination considered as a new mechanical movement, as for instance, where power is applied to the rotary lock screw element for the purpose of producing or preventing certain desired movements of the slip angle screw element.

Considered as a novel mechanical movement usable for translating thrusts or rotative efforts applied to any one of the three elements with the view to producing resultant stresses, movements or locking effects on any other of said elements, the invention may be considered more broadly as a screw element threaded to two other screw elements having the same rate of screw feed, preferably by having the same number of threads per unit length, but having different pitch diameters so that their stress or motion producing resultants are different.

Changing the method of control will make it possible to cause the locking screw to be variously affected, but in the present wrench, the sliding jaw is free to follow or obey any longitudinal external force, except when the wrench is exerting turning moment on the nut in the direction selected. The effect of this is to allow free ratcheting when the wrench movement is reversed, solid locking when operating and a tendency to hug the nut at all times. Because a worm thread is functionally endless and uniform, my present worm locked adjustable mechanism partakes of the nature of a stepless ratchet in which the driven member may be caused to move with the driving member through the latter's full movement or any desired part thereof, according to the timing of the frictional lock, and at the same speed or any lesser speed, according to the degree of frictional lock as governed and maintained by the positively controlled pilot mechanism.

While the locking screw thread and the pilot screw or slipping thread may be formed on separate elements, I show at least one form wherein there is a single deeply-cut threaded screw, the outer or large diameter peripheral portion of which presents a positive locking angle while the innermost part of the groove is steep enough to give an angle of easy slip. In this case two other screw elements are em-

ployed, one having threads adapted to engage the outer part of the groove, the part that has the locking angle, while the other engages only the innermost part of the 5 groove, the part that has the slip angle.

In practically all of the forms shown herein in the threads of the locking screw elements are made to have much more clearance or looseness of fit than are the slip-angle threads, 10 but this is to avoid the necessity for great accuracy in the endwise shift to make one thread or the other take the load. However, either thread can be made to take the load even when the clearance is very small or 15 when the slip thread clearance is greater than the lock thread clearance. In certain forms shown herein, it is the pilot screw element that is given the endwise shift with reference to the locking screw element in order to free 20 the locking threads from locking engagement, bring them to an intermediate position, meshing with, but free from, the teeth of the rack, or equivalent screw element, but it will be understood the shift of the relative positions of the parts, is the functionally important feature, and the matter of which element moves to bring about the shift has to do with the more specific aspects and practical applications of the invention.

30 As before intimated, the shift of control from the locking thread to the slip thread may be only partial or may be momentary. This may be especially desirable under certain conditions as where there is a gravity 35 load on the locking thread and it is desired to lower the load slowly or to a predetermined distance only. In such case special means may be provided for a graduated or partial transfer of some of the load to the 40 slip thread element. In such operation, the torque and thrust stresses on the slip thread may be considerable and the pilot screw element has to be of correspondingly heavier construction.

45 On the other hand, torque and thrust stresses on the pilot screw may be almost eliminated by utilizing an important subsidiary feature of my invention. This contemplates making the worm with its locking 50 threads, and the pilot threads capable of slight relative movement longitudinally but not circumferentially. This may be accomplished by forming the respective threads on co-axial, preferably concentric, sleeves that 55 are connected by a spline. Then, if desired, the pilot sleeve element may be provided with anti-friction thrust-bearings, thereby minimizing the said sleeve's frictional resistance to rotation under load, the factor upon which 60 depend the load-taking capability and resulting stress on the pilot screw. The spline connection also leaves the sliding jaw and the inner pilot sleeve free for a slight end- 65 wise movement with respect to the outer locking sleeve, when the pilot screw rotates the

locking thread into and out of locking engagement with the rack teeth. Upon locking, this permits the end thrust of the full load to be applied by the sliding jaw to the end of the locking sleeve and through the locking thread to the rack, without endwise stress upon the inner sleeve or its endwise thrust-bearing; and upon unlocking, the effect is to immediately permit the outer sleeve to fall free from its end-thrust engagement with the sliding jaw.

70 It will be noted that my mechanism includes inter-engaging elements capable of solid locking under thrust by frictional engagement with each other, in combination with co-acting mechanism controlling the lock by positively controlling said frictional contact.

75 It will also be noted that the locking elements and the pilot elements constitute respectively primary and secondary sets of mechanical transmission elements, the motion transforming ratios of which are fixed and are the same; that the primary elements lock under load while the secondary elements are idle; that the secondary elements tend to rotate under load; that the load may be shifted to the secondary elements; and finally that the two sets of elements are so coupled that rotation of the secondary set under load will cause unlocking and rotation of the primary set.

80 The above and other features of my novel mechanical movement, as well as a variety of special applications thereof, may be more 85 fully understood from the following description in connection with the accompanying drawings, in which

90 Fig. 1 is a side elevation of one form of monkey wrench having one form of my invention applied thereto and with the locking screw element in the locking position.

Fig. 13 is a section on the line 13—13 of Fig. 11.

Fig. 14 is a vertical section of a lifting jack embodying a form of my invention in which the relative movement for shifting the load from the locking thread to make it take effect on the pilot thread may be a partial or intermittent release applied by hand at will.

Fig. 15 is a detail section on the line 15—15, Fig. 14.

Fig. 16 is another vertical sectional view showing another modification of my invention as applied to a lifting jack.

Fig. 17 is a section on the line 17—17, Fig. 16.

Fig. 18 is a longitudinal section of a quite different embodiment of the essential features of my invention, as applied for quick locking adjustment and release of the jaws of a vise, with particular provision for a powerful clamping action.

Fig. 19 is an enlarged detail of the locking and pilot thread elements of Fig. 18.

Referring to Figs. 1 and 2 of the drawings, 1 is the locking thread adapted for rotation and longitudinal screwing movement in mesh, but not necessarily in engagement, with the relatively stationary locking screw element 2, which in this case is a rack, the 20 rack being, functionally considered, a narrow segment of a female screw thread. The locking thread 1 is formed on a sleeve 3 which is rotatably mounted in and carried by the jaw 4, being, in this case, located in 30 a recess between the thrust surface 4^c and the bracket member 4^d. The jaw 4 has sliding engagement with shank 5 to which it is suitably secured by strap or loop portions 4^a, 4^b. The co-operating jaw 6 is rigid with shank 5. 40 Though the significant movements and stresses are all relative, it is convenient, for descriptive purposes, to consider the jaw 6, shank 5 and rack 2 as fixed and other parts as movable with reference thereto; and, although the working pressures on jaws 4 and 6 are equal and opposite, the manipulating pressures are on one jaw only, and it is convenient to consider the sliding jaw 4 as the load carrying member.

50 The pilot screw 7 has a pilot thread in the form of a groove 8 which is in threaded engagement with the interior projecting lugs or thread elements 9. Said interior thread elements 9 may be formed directly on the interior of the sleeve 3 which has the locking thread on the exterior thereof. Preferably, however, said threads 9 are in a separate sleeve member 10 which is splined to locking sleeve 3 by means of screw 11, fitted into a 55 spline groove 12 so that sleeve 3 is free for slight relative movement longitudinally but is locked to sleeve 10 so far as concerns rotary movement.

60 The pilot thread 8 has the same number of turns per inch as locking thread 1, but the

pitch is steep enough to permit easy slip and rotation of one of the pilot elements 7 or 9, by the other, in response to endwise pressure of either or both with respect to the other. In the present case the pilot screw 7 is non-rotatable with respect to jaws 4 and 6 and shank 5, so that sleeves 10 and 3 and locking thread 1 carried by the latter, are the elements that rotate when there is relative longitudinal movement.

Whether the locking thread or the pilot thread will control will depend on whether or not the pilot screw 7 is endwise supported with its threads 8 in phase or registry with the locking threads 1. If out of phase, as when screw 7 is in the lowered position, the load will be applied through jaw 4 and thrust surface 4^c directly to the sleeve 3 and locking threads 1 to the rack teeth 2 and through them to shank 5 and co-operating jaw 6.

When the pilot screw 7 is longitudinally supported in the upper position, a load applied on jaw 4 in the direction of arrow "X" will not be supported by the slip angle groove 8, and jaw 4 will move downward along the pilot screw and the locking screw threads 1 will not thereby engage and lock against rack 2, because said longitudinal movement will rotate the locking worm thread 1 at exactly the required rate to keep said thread 1 out of frictional lock engagement with the teeth of rack 2. Moreover, when the pilot screw 7 is deprived of its endwise support, the locking threads 1 will immediately engage the teeth of rack 2 and will lock the jaw 4 against further retreat. Hence, in order to have the sliding jaw either free or locked at will, it is only necessary to give the pilot screw 7 a slight endwise shift.

As shown in the drawings, this is accomplished by providing the lower part of shank 5 with a handle member preferably in the form of a light sheet metal casing 13, pivoted on bolt 14 and carrying a suitable cam surface 15, in position where it will apply endwise thrust and support upon said pilot screw 7 when the handle swings in one direction as for the screwing pressure; and will remove said thrust and support when the pressure is applied on the handle in the opposite direction.

The shank 5 has a transverse member 16 secured by studs 17 and screw 18, which is formed with a slot 19, engaged by a spline pin 20 extending through the lower end of the pilot screw 7. The pilot screw 7 is normally thrust downward against cam surface 15 by means of an encircling spring 21, which, at one end, engages collar 22 on screw 7, and at the other end, an inwardly extending annulus 23 of nipple 24, which latter is screw-threaded in bracket 4^d. The spring 21 thus exerts upward pressure on sliding jaw

4, whereby the jaws will automatically close when unlocked from the rack 2.

The cam surface 15 may be afforded by a stud member 25, mounted in an end piece 26, secured by cross bolts or rivets 27 in the bottom of handle 13. This cam stud is made rotatable so that it can be held in any one of several positions by means of locking screw 28 engaging one or the other of recesses 29, 29^a, 30^a, or 31^a. (See Figs. 4 to 7 inclusive.) As shown in Fig. 2, the screw 28 engages recess 31^a, and in this position, applying transverse stress to the handle 13 in the unlocking direction, will bring it to the position shown in Fig. 2 where the handle is in firm contact with one end of member 16, in which position the pilot screw 7 has the thrust surfaces of its thread groove 8, controlling the locking screw and the threads of the latter will be maintained out of locking relation with teeth 2, as shown in said Fig. 2. In this situation, the sliding jaw 4 is entirely unlocked and may be moved freely in either direction, with or against the pressure of spring 21. It may be retained against said pressure by a finger or thumb of the user engaging lugs 4^e or 4^f, which are provided for this purpose.

When the direction of pressure on handle 13 is reversed, however, the handle will come in solid contact with surface 30 of shank 5, in the position shown in Fig. 1. In this position, the cam surface 15 permits retreat of pilot screw 7 under the influence of spring 21, with the result that the locking thread 1 immediately engages rack teeth 2, as shown in said Fig. 1.

This results in a monkey wrench wherein pressure applied to the handle toward the left will lock the sliding jaw 4, as shown in Fig. 1, while pressure toward the right will release the sliding jaw, as shown in Fig. 2. Thus the jaws will automatically ratchet around the head of a bolt or nut in response to the screwing and resetting pressures. The lighter the spring 21, the lighter will be the ratcheting stress, but the slower will be the reseating of the jaws; but in general a light spring is desirable and in practice its lightness will be limited by the weight of jaw 4. Hence this part may desirably be made of "duralumin" or similar aluminum alloy.

As it is desired to make the locked position the normal position, I provide a bell crank lever 31, mounted on pivot 32 and tensioned in the proper direction by spring 33. It will be remembered that in this normal locked position, the worm sleeve 3 may be adjusted by hand operation after the manner of the ordinary monkey wrench.

The unlocked position of cam plug 25 is shown in Fig. 4, and the locked position in Figs. 2 and 7. Said plug 25 is rotatably mounted and the locking screw 28 is provided for the purpose of permitting adjust-

ment and locking thereof either to the position of Fig. 7, the result of which is to reverse the direction of pressures which will lock or unlock; or to the position of Figs. 5 and 6 wherein the cam is altogether inoperative because the lower end of the pilot screw is bevelled off as at 7^a so that the cam swings by without contracting and the pilot screw remains in the lowermost position no matter which way the handle is stressed. In the latter position the jaw 4 may be adjusted by hand rotation of worm 3, as above described.

The various positions of cam plug 25 may be exteriorly indicated by a pointer 25^a.

The main function, so far as above described, would be performed, even if sleeves 10 and 3 were integral. An important feature, however, is making them separate and splining sleeve 3 on sleeve 10, as above described. In the specific arrangement shown in Fig. 2, the inner or pilot sleeve 10 is provided with ball bearings to eliminate frictional resistance to rotation. The upper bearing is afforded by ball 35, in race 36, having an internal retaining lip 37, the function of which latter is mainly to prevent the balls from falling out, particularly while the parts are being assembled. The lower bearings comprise balls 38 in a similar race in the lower end of the sleeve 10, the other bearing surface for the lower balls being the annulus 23 previously mentioned. Obviously, if the sleeve 10 were integral with locking sleeve 3, these balls would have to take the full thrust of the maximum strains that can be applied on the sliding jaw 4 and in practice these strains would be likely to exceed the crushing resistance of any balls suitable for use in such a position. Hence one feature of invention and advantage involved in making the locking sleeve 3 capable of slight longitudinal movement with respect to pilot sleeve 10, is that it permits the solid thrust surface 4^e to take the load and relieve the balls of all load. An incidental advantage is that the friction of surface 4^e at the end of sleeve 3 becomes available as part of the friction lock factor, making it possible to use a locking thread 1 of steeper pitch than would otherwise be possible; this in turn making it easier to get a slip angle pilot screw of the same pitch as the locking thread.

The spline connection 11, 12, leaves the sliding jaw 4 and the inner pilot sleeve 10 free for a slight endwise movement with respect to the outer locking sleeve 3, when the pilot thread 8 rotates the locking thread 1, into or out of locking engagement with the rack teeth 2. Upon unlocking, when the pilot screw 7 is given its endwise, forward movement, it thereby rotates the inner sleeve 10, spline 11, and the outer sleeve 3, to free the locking threads 1 from engagement with the rack 2, whereupon, the spline connection permits the outer sleeve 3 immediately to fall free from

its frictional end-thrust engagement with surface 4^c on the sliding jaw 4. Upon locking, when the pilot screw 8 retreats endwise, its first effect is to take up the back-lash in its own thread; then, to rotate the inner and outer sleeves to bring the locking thread into engagement with the rack teeth; and thereafter upon further rotation the spline permits the locking thread to take out its own back-lash by screwing itself along the rack 2, into firm engagement with surface 4^c on said sliding jaw 4, thereby affording a solid path of thrust from the sliding jaw through the outer or locking sleeve and thread, to the relatively stationary rack, without endwise stress upon the inner sleeve.

When the retreat of the pilot screw is by spring pressure, the automatic elimination of all back-lash presupposes a spring strong enough to do the work, which may not be necessary or desirable, in certain cases. Preferably the clearance between pilot thread elements 8 and 9, that is, back-lash or looseness of fit measured lengthwise of the pilot screw, is less than the clearance between the locking thread elements 1 and 2, in which case the pilot screw will take the load and will permit free sliding of the jaw 4 in both directions. As considerable back-lash is unavoidable in the pilot screw because of the acuteness of an angle along which back-lash is measured, I prefer to make the pilot screw back-lash or clearance as small as practicable and make the locking thread clearance relatively great. Fortunately the permissible margin for this is ample since the spaces between rack teeth 2 may be cut very wide before there is danger of weakening them below the maximum load limit.

In certain cases, however, it may be desirable to make the pilot screw clearance greater than the locking screw clearance, in which case the pilot thread groove can have only one of its working surfaces in position to take load and unlock the locking screw. In such case, the pilot screw may be held to a midway position where it is inoperative and the locking screw locks against thrust in both directions; or by shifting one way or the other, there will be sliding in one direction and lock in the other, but there is no position permitting free sliding in both directions.

The inner sleeve 10 is held in axial alignment with its thrust bearing by sleeve 3 of which a reduced portion 40 has sliding fit within a recess in sliding jaw 4. At the other end sleeve 3 has an interior bearing 41 on nipple 24 and a washer 42 prevents longitudinal displacement of the reduced portion 40 out of its bearing.

In all of the foregoing, the pilot screw never has to sustain any important endwise thrust; hence it can be made quite small, to give a high pitch to its thread on a limited predetermined number of turns per inch.

Nevertheless, in practice, it may be desirable to cut the pilot groove quite close to the axis, in order to get the desired easy slip angle, where the locking thread is of particularly low pitch. Hence, as shown in Fig. 3, I prefer to employ a pilot screw of substantial diameter and form the pilot thread as a groove cut in as close to the axis as may be necessary for the purpose in view, the outer portion of the groove being cut away as at 8^a, so that only the inner portion 8 functions as a screw thread.

The pilot screw 7 and encircling spring 21 are preferably protected by tube 44, rigidly screwed to the sliding jaw bracket 4^d and having loose sliding fit in filler piece 45, secured in handle 13 by lugs 46.

While the various details of my invention above-described as embodied in this type of monkey wrench are novel and are of considerable practical importance, all except the more basic features of function and construction are capable of wide variation as will be evident from the forms hereinafter described. In some of these the similar shapes and structures will be obvious while in others they are shifted about and combined with new elements making identifications more difficult.

In Figs. 8, 9, and 10, the broad essentials of the invention are applied to another form of monkey wrench; the external appearance is that of another well-known commercial form. The basic elements and their cooperating functions are essentially identical with those just described in detail in connection with Figs. 1 to 7. In so far as concerns generic features, and except for the differences which I will now describe, the preceding general statements with reference to my first described form of wrench may be taken as applying to the various embodiments described hereafter.

In Fig. 8 the similar basic elements are the locking threads 51 on rotatable sleeve 53, and the locking thread element 52 on a member which is longitudinally movable with respect to the sleeve; also the pilot screw 57 with slip-angle groove 58, engaging interior slip-thread elements in said rotatable sleeve 53; also the spring 71 which has the double function of pressing the lower jaw 54 to the closed position and also forcing the pilot screw to inoperative position when the endwise thrust of the operating cam 65 is removed. The shank 55, integral fixed jaw 56 and the sliding jaw 54, with strap or loop members for retaining it in engagement with shank 55, will also be recognized. An important practical difference is that the handle is solid, has no oscillating movement, and may be shaped precisely according to the old standardized designs. In Fig. 8, the rotating locking-screw element 51, 53, is now associated with the fixed jaw and shank 55, being rotatably mounted thereon in a step bearing 13.

54^c, and retained against withdrawal by knurled flange element 54^x, extending under projection 54^a on shank 55. This rotatable locking screw element 51, 53, is elongated to the full length of the throw of the slidable jaw 54, while the non-rotatable locking screw element 52 is short, just the reverse of the length relations of the rack 2 and the worm 1 in Figs. 1 and 2; and said rotary locking element 51, 53, is now associated with and carried by the sliding jaw element. Said pilot screw 57 is held from rotation while being permitted the required longitudinal movement by a guide sleeve 72, having a slot 15 engaged by spline pin 69 which passes through the rear end of the pilot screw. The sleeve 72 is screw threaded into the sliding jaw and is locked in place by key screw 68.

The handle being rigid in Fig. 8, other movable means must be provided for giving the pilot screw 57 the required endwise shift to throw it into locking or unlocking position. The cam surface 65 for performing this function is formed on a separate jaw-25 face element 80, the upper face of which forms the work-engaging face of the sliding jaw. This supplemental, working-face element of the sliding jaw is preferably the full width of the jaw. It is knurled at the sides 30 as at 81 to afford a good holding grip whereby it may be moved transversely by hand to throw the cam surface 65 into and out of displacing position at the rear end of the pilot screw 57. The slidable face piece 80 is 35 formed with a dove-tailed portion 82 depending into a correspondingly shaped recess in the sliding jaw. The face piece, being inserted in the sliding jaw before assembling, is then safe from sliding out at the front. 40 The slidable face piece is also provided with a recess 83 for holding one end of a thrust spring 85, the end of which butts against a suitable surface on the slidable jaw at 84.

The spring 71 bears at one end on the bottom of recess 71^a in the handle of the wrench and at the other end upon a collar 86 swivelled on the end of pilot screw 57. The pressure of the spring on this collar has the primary effect of forcing the pilot screw as far back as the cam will let it go and thereafter the further effect of pressing the slidable jaw to the closed position. Obviously, the slidable face piece 80 may be pulled out or pushed in by hand the distance necessary to 55 give the endwise cam thrust and retreat of the pilot screw 57, which will put it into and out of unlocking relation with the locking screw 51.

There is, however, a further and more important capability of operation. When the jaws are open and a nut of ordinary dimensions is clamped between them, with its centre at a point indicated as at C, Fig. 8; then a rotary effort on the handle in the direction 60 of the arrow R will give a stress on slidable

face piece 80 in the direction of arrow S, the horizontal component of which, as indicated by arrow M, tends to force such slidable element to the right moving cam 65 in the direction for releasing and permitting retreat of the pilot screw 57, to the inoperative position, thereby causing the locking thread 51 to lock the sliding jaw against opening. Reverse pressure, however, applies a reverse sliding component to face piece 80, forcing cam 65 under the pilot screw 57, thereby thrusting the latter downward to cause rotation and unlocking of the locking screw. Hence, this device will automatically lock and unlock in response to alternate pressures applied on the handle; and will ratchet around and hug a nut or bolt head, as in Figs. 1 and 2; but the cause will be the reversals of stress and movement of the jaw face by the reversing pressures on the nut, instead of 80 pivotal movements of the handle.

The spring 85 normally tends to keep the cam piece in the rearmost position and whatever wedging action there is by the pilot screw 57 under the pressure of screw 71, affords a further pressure in the same direction. Under certain conditions, however, a tension spring such as the spring 185 of Fig. 11 may be substituted for the spring 85 in which instance, it would be easier for the jaw 80 to slide outward and overcome the excess pressure of spring 71 and the bed of the face piece 80 would be slightly inclined to give said face piece a pressure responsive bias toward either the locked or unlocked position of the same.

For convenience in manufacture and assembly, and also for the functional advantages, the jaw 56 and shank 55 may be integral, the lower portion 55^a being shaped to fit the hand. Portions 55, 55^a, will be small enough to pass through the straps 54^a, 54^b, of the sliding jaw, which latter will be applied thereover after the face piece 80, with backing spring 85, have been inserted therein from the rear. The locking screw sleeve 53 may be then screwed into 52 just far enough to give the member 54^x a loose fit against 54^a when the jaws are closed. Thereupon the supplemental handle section 55^b is applied and secured by screw bolts 55^c. The section 55^b is additionally secured against the endwise strain by means of the endwise thrust shoulder 55^d.

It will be noted that in this device the locking sleeve 53 takes the entire endwise load over the sliding jaw, but its permissibly great diameter and tubular form well adapt it for sustaining such thrust. There is, of course, no load on the pilot screw except that necessary to rotate locking sleeve 53 at a time when the latter is relieved of its load.

In Figs. 11 and 12, I have shown another rigid-handle embodiment of my invention 120 as applied to an S type wrench, wherein the

jaw opening is presented outwardly endwise of the handle. In this form, certain features are so substantially like some of the parts in Fig. 2 that I have given them the same numerals, while others are similar in function more than in form. The locking threads 1 are on the exterior of a sleeve 3 which is movable longitudinally but not circumferentially on inner sleeve 10, having interior pilot screw elements 9, the driving connection being through spline screw 11, engaging spline groove 12. In the present form, Fig. 11, the inner sleeve 10 is not provided with ball bearings, but the spline association with locking sleeve 3 relieves sleeve 10 of all endwise thrust exactly as described in connection with Fig. 2. The pilot screw 107 has the same functions as in both the preceding forms while the sliding jaw piece 180 carries a cam surface 125, adapted to endwise shift the pilot screw to release the locking thread 1. There is also a spring 121 tending to close the "movable" jaw 104 against the "fixed" jaw 106, and also to thrust the pilot screw against the slidable cam surface 125.

The pilot screw element 107 is functionally associated with the slidable jaw and its endwise movement is controlled by and from said jaw, although said pilot screw element is actually housed in the fixed jaw member. This is made possible by use of a pilot screw rod or extension member 127, slidably mounted in the sliding jaw 104, and having a depending portion 128, the lower end of which is secured to the rear end of the pilot screw element, preferably by pivot 129. The device further differs from any of the preceding in that the rack 102 is on the slidable jaw.

Because of the transverse disposition of the moving parts, the spring 121 for holding the pilot screw extension 127 against the cam 125 is curved around an anti-friction roller 130 and extends down into a tubular cavity 131 in the handle. The face piece 180 of the slidable jaw is normally pressed outward with its cam element 125 in contact with the cam 126 of the pilot rod by means of a contractile spring 185. In this case the spring 185 acts in opposition to spring 121 in contrast to the arrangement in Fig. 8, wherein spring 85 acts in harmony with spring 71. Consequently spring 185 must be substantially weaker than spring 121, and its purpose is to make the face piece 180 more sensitive to unlocking efforts.

In Fig. 11, as in Fig. 8, the locking screw can always be rotated by hand even when the pilot screw is in the position for locking.

In all the forms shown in the Figs. 1 to 13, inclusive, the strength, proportion and arrangement of the parts is designed with a view to performing the unlocking operation at a time when the load is removed or min-

imized on the sliding jaw, as by relief or reversal of pressure on the handle. The broad principles of my invention, however, are applicable to devices wherein the load on the slidable member is continuous and very heavy. In such case, the relative movement of parts necessary for unlocking might be by sufficiently powerful endwise thrust applied on the pilot screw. Preferably, however, the shift of phase between the locking thread and the pilot thread is accomplished by movement of some other one or more of the two pairs of thread elements, one expedient being provision for slight relative rotation of the otherwise non-rotatable member, that is, a member corresponding to the rack in Figs. 1, 2 and 11 and corresponding to the thread 52 in Fig. 8.

The conditions of heavy, continuous load, and necessity for release under load, are found in lifting jacks, illustrative examples of which, embodying my invention, are found in Figs. 14 to 17, inclusive.

In Figs. 14 and 15, the outer load screw of the jack is the relatively rotatable and longitudinally movable locking screw element. It comprises the locking thread 201 on the outside of the tubular sleeve 203. The co-operating, normally stationary, locking screw thread 202 is longitudinally fixed with reference to the stationary casing 205, but, for a purpose described below, it is formed on a separate sleeve member 205^a, supported by shoulder 205^b and held in position by a screw 205^c engaging circumferential recess 205^d, which permits slight rotary movement of the locking thread 202 with respect to casing 205.

The pilot screw 207, having a pilot groove 208, is fixed against both longitudinal and circumferential movement by a pin 208^a, keying it to base 205^e, which is secured to standard 205 by bolts, as at 205^f. The co-operating pilot thread element 209 is on the inner face of an inner tube or sleeve 210, which is rigidly connected to locking screw sleeve 203 through cap plate 236 to which pilot sleeve 210 is secured by key 237 and locking sleeve 203 by dowel pin 212. Thus the outer locking screw sleeve 203 and the inner pilot tube 210 revolve and lift as a solid unit.

In order to rotate this unit to screw up the load, there is an inner driving tube 238, secured to bevel gear 239 by key 240. Gear 239 is journaled on an enlargement 241 on the base of the pilot screw 207 and is itself driven by pinion 241 which is, preferably, arranged at a slight angle to the horizontal, and is journaled in casing 205, as at 242. It is held from endwise movement by collar 243, secured by key pin 244. The outer end of 245 is squared so that an extensible socket handle can be applied, removed and operated without the necessity for the operator to stoop, the inclination of the pinion axis be- 130

ing such as to bring the outer end of the handle approximately to the waist-line of the operator.

When the pinion and gear are thus rotated, and thereby the driving tube 238, the rotary movement is imparted to the locking screw through spline key 246 which has a sliding fit in groove 247 in said tube 238.

In this lifting jack, as in the preceding device, the pitch angle of the locking screw thread is such that the thread friction under load, plus the other resistances to rotation, affords prohibitive resistance to any automatic unscrewing of the locking thread by pressure of the load. In this case also, as in the others, the pilot thread has the same number of turns per unit length as the locking thread and has a steep slip angle, so that it easily rotates inner pilot sleeve 210, cap plate 236, and outer locking sleeve 203.

In the present case, the clearance space in the groove of the pilot screw element is greater than the clearance space between the threads of the locking screw element, instead of being less, and the desired shift of load from the locking threads of the pilot threads is accomplished by rotating sleeve 205^a. The means for rotating and locking the sleeve 205^a in various positions is a handle 247 pivoted at 248 in ears 249, on said sleeve. The handle is formed with a locking projection 250 adapted to engage a suitable recess 251, for locking the sleeve in the midway position where the pilot screw is totally inoperative because its clearance is greater than that of the locking threads. The other two positions will be circumferentially distant from 251 by the amount required for advancing or backing threads 202 to the positions required for shifting to and from the pilot screw, either the up-pressure of spring 221 or down-pressure of a load being supported by the jack.

There are three characteristic positions for the sleeve 205^a.

First, the one shown in the drawings where the locking projection 250 is in recess 251 and the locking threads 201 have their top surfaces in contact with the bottom surfaces of threads 202, being thrust thereagainst by spring 221, but the pilot groove threads are not in contact because of the above-described greater clearance or looseness of fit of the latter. If load be applied to the top of the jack as by rotating the gears in the proper direction, the result will be to shift threads 201 downward so as to bring their lower surfaces in thrust relation to the tops of threads 202, but pilot projections 209 will still be out of contact with the bottom faces of the pilot grooves. In other words, the pilot screw is wholly inoperative as regards any thrust, whether upward or downward. Consequently, the jack is automatically held in the collapsed position against the thrust of the powerful spring 221, and at the same time

is free to be screwed up or down by means of the gears.

Second, the position of the sleeve 205^a, wherein its rotation has screwed upward and lifted sleeve 203 and through it the pilot sleeve 210 until the pilot threads 209 have come in contact with the top of the pilot groove. Motion to this position may be limited by a suitable stop. This position is of practical importance because it permits the locking sleeve and pilot sleeve to shoot upward under the thrust of spring 221, the pilot groove screwing the locking threads at the rate necessary to permit this. This brings the jack instantly under the load and return of the handle to the first position will permit lifting the load by rotating the gears, as above described.

Third, rotating sleeve 205^a to back off the thread 202 from support of thread 201, thereby lowering the locking sleeve and through it the pilot sleeve to the extent necessary to make pilot threads 209 come into contact with, and apply thrust upon, the bottom of the pilot groove, thereby slipping therein and rotating the locking sleeve to automatically screw the locking threads 201 downward. Such downward screwing will be at a speed proportional to the completeness with which the locking threads have been relieved of the load and the pilot threads have taken load. Thus the handle 247 may be used as a throttle to lower the load slowly or rapidly or intermittently.

The practical effects of this mechanism are to produce a jack which can be placed in a position under a load to be lifted and by a simple operation of the lever, the jack can be caused to automatically jump to a position directly in contact with the load so that the first operative movement will immediately result in a lifting action. Throughout the range of lift, the jack operates as an ordinary jack. When it is desired to lower the load, the jack can be automatically transformed from an absolute load retaining mechanism to a collapsible mechanism, collapsible under the action of the load itself. At all times, the lowering of the load is under absolute control of the operator as regards speed or distance, since the load, even though in downward motion, may be stopped at any desired point. Another feature is that the load retaining threads themselves act as a brake.

In order that the screw structure may rotate easily under load, I provide a pressure cap 252 and interposed ball bearings 253. The cap 252 preferably has its upper surface roughened to prevent the load from tending to slip at any time. The ball thrust bearing is enclosed in the dirt proof chamber formed in the interior of cap 252, the latter being secured by screw 254 engaging groove 255. It should be noted that the screw sleeve 203 and cap piece 236, as an upper rotating and sliding element, and bevel gear 239 and driv-

ing tube 238 as a lower rotating element, form a pocket whose upper and lower surfaces revolve at the same rate of speed but whose length changes as the load is lifted. This pocket contains the heavy thrust spring 221.

The ball bearings minimize the torque load on the pilot screw when lowering. Hence the latter may be of smaller size and will slip with less pitch angle.

In the modified forms of lifting jacks shown in Figs. 16 and 17 are found practically all of the important functions described above in connection with Figs. 14 and 15, including the rotary adjustment of the normally stationary locking screw element to the characteristic three positions whereby the pilot screw may be rendered entirely inoperative, or operative in the up-direction under the impulsion of the heavy internal spring, or in the downward direction under the impulsion of the load. These features are embodied in practically the same number and kind of operating elements, but the heavy external casing and the bevel gears and the driving tube 238 have been dispensed with and a ratchet has been substituted at the hand screwing means.

The load bearing cap swivelled on ball bearings requires no description. The connection of the exterior locking sleeve 303 with the internal pilot sleeve 310, through cap piece 336, pin 312, and key 337, are substantially the same as in Fig. 14. The structural arrangement and disposition of the operating elements involve important features of novelty and advantage.

The locking thread 301 is on the inside of sleeve 303 and the co-operating locking threads 302 are on the outside of a tubular member 305^a, which, instead of being short like the corresponding part 205^a, in Fig. 14, extends down to the base of the machine and constitutes in effect the stationary standard of the jack, surrounded and protected by the sleeve 303. This arrangement is obviously neater and affords better protection of the screw threads from injury and from dirt.

The said member 305^a is rotatably mounted on the stub standard 305, which is integral with base 305^c. It has an ample thrust bearing for carrying the load at 305^c, and is secured against withdrawal by pivot screws 349, fitting annular groove 305^a. The means for rotating sleeve 305^a to the three characteristic positions above described consist of a fork 348, pivoted at 349 and provided with a socket 350 for insertion of an operating handle. The locking in the operating position is by engaging of the socket member in a recess for between lugs indicated in dotted lines at 351.

The rotation of the locking thread 301, by hand, to lift the load, is by means of a ratchet applied to the exterior of sleeve 303 which is

formed with a circumferentially disposed series of ratchet teeth 352. The ratchet housing 353 is supported by engagement with the tops of the ratchet teeth as at 354, and is prevented from upward displacement by split spring ring 355, sprung into groove 356. The ratchet pawl 360, pressed forward by spring 361, is slidably mounted in a shell 362 which is, in turn, slidably mounted in an opening 364, intersecting the ratchet cavity at right angles. The shell 362 and the pawl carried thereby are normally pressed outward to inoperative position by spring 366 engaging head 367. The pawl is rotatably mounted in shell 362, but is normally held with its operating face 368 parallel with the ratchet teeth by pin 369, engaging groove 370. The rear of the pawl is provided with a knurled extension 371, whereby the direction of its working face and the resulting ratcheting operation may be reversed. The pawl, spring and shell 362 are adapted to be forced inward to an operating position against the pressure of spring 366 by insertion of a tapered end of the operating bar or lever through transverse opening 372. The bar opening 373 through the pawl is enough larger than the bar opening through the shell to permit of the necessary reciprocation of the pawl without interference by the bar. An advantage of this construction is that when the bar is withdrawn and the releasing fork operated to permit the jack to run down under pressure of the load, the pawl being automatically disengaged, the shell 362 does not have to rotate with the ratchet teeth and hence is not dangerous when lowering the load at high speed.

In Figs. 18 and 19, I have shown a device in which the essential elements of the invention are embodied somewhat differently from any of the preceding. The exterior appearance of the vise is more or less conventional, comprising a fixed jaw 404, integral with base 405, and a movable jaw 406, having a shank 406^a, which is longitudinally slidable with respect to the fixed jaw and slidably held by the encircling portion 404^a.

The locking thread 401 and the pilot thread 408 are in the same groove of a single screw 478. The cooperating locking screw element 402 is a shallow thread integral with the fixed base 405 and is analogous to the rack 2 on shank 5 of Figs. 1 and 2. The co-operating pilot screw element 409 is a deep thread on the interior of nut 410, which latter is capable of slight longitudinal movement with reference to locking screw element 402, being supported by longitudinal bolts 410^a and 410^b, slidably engaging the portion 403 of base 405, and normally tensioned rearwardly by spring 421, engaging bracket 422, on base 405. In this form the clearance of the pilot screw threads is small, much smaller than the clearance of the locking screw threads which latter

have substantial clearance for a reason explained below.

The feature of having a locking screw and pilot screw made in one piece depends on the principle that, as any screw thread is cut deeper, the angle of inclination toward the centre will be far greater than the angle of the outer periphery, even though the pitch be the same. Advantage of this is taken by using the outer periphery as a locking angle and the inner portion as the slip angle. In the construction of the vise, since the locking screw is a tension member, it is more practicable to use such a construction than where the screw member is used in compression; because a tensile stress will always tend to keep a screw straight, whereas a compression stress would have a tendency to bend it.

The forward end of the screw member 478 rotates in a double thrust ball bearing 425, the inner race of which is held rigidly to the screw by a threaded nut 430, which, in turn, is immovably locked to the screw by pin 431. The outer race collar of this ball bearing is slidably mounted in the sliding jaw member 406 between thrust disc 432 on one side and the spring 433 on the other side. The operating handle 434 for the vise is on a loosely rotatable hub member 435, which has turned in it a ring groove 436, engaged by a pin 437, which permits rotation but limits its axial movement at all times. The inner face of the hub is formed with jaw clutch projections 438 adapted to be moved into and out of engagement with co-operating clutch projections on the threaded nut 430, which is pinned on the end of the screw 478.

In operation the handle 434 would be pulled forward. This would transmit the pull through the pin 437 to the sliding jaw. The sliding jaw would then transmit this pull through the spring 433 to the ball bearing 425, which is mounted on the locking jaw, and thereby to the screw 478.

The outer or locking thread element 401 of the screw is normally free from locking engagement with the locking thread element 402, but the inner periphery or slip angle thread is in engagement with the pilot nut 410, which may move forward. The forward pull on the pilot nut is resisted by the spring 421. Spring 421 holds the pilot nut back hard enough so that when the screw 478 has been pulled the slight distance necessary to free locking threads 401, 402, (as in Fig. 19), the screw 478, which then bears only at the slip angle thread 409, will begin to rotate rapidly, thereby screwing the locking threads at their proper rate and allowing the sliding jaw to move forward freely. The maximum load the ball bearing takes is governed absolutely by the strength of the spring 433, and this thrust in no case should be more than the pull necessary to cause the screw to rotate on its slip angle thread.

When the work to be clamped by the vise is inserted between the jaws, the sliding jaw 406 may be pushed backward until the jaws close on the work. Operating handle 434 is then pushed backward, the jaw clutches 438 on the hub 435, and on 430, are caused to engage and rotation of the handle 434 will then cause corresponding rotation of the locking screw member 478. The first effect of this rotation will be to rotate the screw member 478 on the pilot nut 410 as a base until the clearance between the rear of clutch member 430 and the front of thrust disc 432 on the sliding jaw is taken up. Further rotation will cause locking screw element 401 to contact with the stationary screw element 402, take out the slight clearance in the threads at this point and then tighten the jaws of the vise on the work with a non-releasable grip. While this non-releasable grip is being applied the pilot nut 410 is fed forward by the slip screw thread and against the pull of spring 421, but the clearance provided between the forward face of the pilot nut 410 and the rear face of stationary element 403, is sufficient to prevent the pilot nut from jamming the stationary nut. In this operation, also, the ball bearing is loaded only with the resistance of spring 433, and we have helping us in the locking stage both the friction of the locking threads and the friction of the rear face of jaw clutch member 430, on the front face of thrust disc at the surface where there was previously a clearance.

The pilot nut 410 is itself slidably guided to the stationary nut 403 by means of the screws 410^a and its backward position is limited by the length of said screws. The locking screw thread 401 is substantially clear of radial frictional resistance when pull is being exerted on screw 478 through handle 434; the resistance to rotation being then comprised only of the inertia of the moving parts, the ball bearing resistance and the frictional resistance in the pilot nut itself. Hence only a very small axial force need be applied to cause the sliding jaw to slide either in or out.

This construction allows the vise to present an external appearance which is practically identical with that of existing types.

In this application I have described the pilot element as being a screw having the same pitch as the locking screw element and adapted to rotate the locking screw element at the proper rate of speed, while the latter is either in partial contact or entirely out of contact with its co-operating locking member; but my invention in its broadest aspect contemplates a mechanical movement broadly comprising locking members, a pilot member for controlling the state of lock or unlock, by its ability to rotate the locking member at a definite rate of speed and means for positively shifting the phase relation of the locking, pilot members whereby the de-

gree of frictional contact may be varied at will and may be held constant for any period of time. This will broadly include the same or different forms of locking members, preferably toothed, and a different form of pilot mechanism which may include toothed gearing of the proper size, chain belts, or other positive-ratio, motion-transmitting mechanism. Such combinations are perhaps more applicable to the field of change gear mechanisms, variable intermittent mechanisms, stepless ratchets, and specific disclosures as to these are reserved for an application or applications about to be filed.

Many of the following claims are broad enough to cover the embodiments of the invention shown in all of the figures of the drawing and the variety of the forms helps to emphasize their broad scope. The remaining claims, some of them quite specifically, are all readable on the form of the invention shown in Figs. 1 and 2. Specific claims for the more specific novelty of the embodiments shown in Figs. 8 to 19 will be presented in the divisional applications about to be filed.

I claim:

1. In releasable thrust mechanism, continuously intermeshed thrust-receiving elements which are normally locked against movement in response to thrust, in combination with shiftable pilot mechanism for relatively moving said elements out of locking engagement and for then moving the relieved elements to maintain such relief relation while the thrust receiving elements are moving in the direction of the thrust.

2. A thrust-receiving member mounted for movement in the direction of the thrust and a support therefor locking by friction against yield in the direction of the thrust, in combination with a pilot mechanism including an element shiftable to relieve frictional locking resistance, and means for utilizing thrust applied by said thrust-receiving member, to drive the relieved locking support element in the direction of thrust applied by said thrust-receiving member, at the rate required to prevent re-locking.

3. A thrust-receiving member mounted for movement in the direction of the thrust and a locking support therefor, in combination with a pilot mechanism including an element shiftable to unlock said locking support, and means for utilizing thrust applied by said first member, to drive said locking support in the direction of thrust applied by said thrust-receiving member.

4. In releasable thrust mechanism, continuously intermeshed thrust-supporting elements which, in the direction of the thrust, are in reciprocal thrust relation and normally locked against movement in response to thrust, in combination with shiftable pilot mechanism for relatively moving the thrust elements to relieve locking engagement and

for then causing relative movement of the relieved locking elements through distances and at rates necessary to maintain the thrust-relief relation, while the parts are moving under thrust applied in either direction. 70

5. Releasable thrust mechanism including toothed thrust-supporting members having backlash upon reversal of thrust and normally locking by friction when the backlash is taken up, in combination with shiftable pilot 75 mechanism for relatively moving such members in the direction to relieve thrust pressure on their frictional locking surfaces and for then driving them at the rate required to maintain such relief while the parts are moving under the thrust.

6. In releasable thrust mechanism, toothed thrust-supporting members which, in the direction of the thrust, are continuously in mesh but with clearance affording backlash upon 85 reversal of thrust and normally locking by friction when the backlash is taken up, in combination with shiftable pilot mechanism for relatively moving such members in the direction of said clearance to relieve thrust 90 pressure on the frictional locking surfaces and for then driving the relieved toothed member at the rate required to maintain such relief while the parts are moving in the direction of the thrust. 95

7. In releasable thrust mechanism, toothed thrust-supporting members which, in the direction of the thrust, are in reciprocal thrust receiving and transmitting relation but with clearance affording back lash upon reversal 100 of thrust and normally locking by frictional engagement when the back lash is taken up in either direction, in combination with shiftable pilot mechanism for relatively moving such members to afford clearance between 105 the thrust transmitting and receiving surfaces in both directions, and for then driving the relieved toothed member at the rate required to maintain such relief while the parts are moving under thrust applied in either 110 direction.

8. A thrust-receiving member mounted for movement in the direction of the thrust and a locking support therefor, in combination with a pilot mechanism separate from said thrust receiving member including an element shiftable to unlock said locking support, and means for utilizing thrust applied by said thrust-receiving member, to drive said locking support element in the direction of 115 thrust applied by said thrust-receiving member.

9. A thrust-receiving member mounted for movement in the direction of the thrust and a support therefor locking by friction against 125 yield in the direction of the thrust, in combination with a pilot mechanism including an element shiftable to relieve frictional locking resistance, and means for utilizing thrust applied by said thrust-receiving member, to 130

- drive the relieved locking support element in the direction of thrust applied by said thrust-receiving member, at the rate required to prevent re-locking.
- 5 10. A thrust-receiving member mounted for movement in the direction of the thrust and a lock screw support therefor, in combination with a pilot screw mechanism including an element shiftable to unlock said locking screw, and means for utilizing thrust applied by said thrust-receiving member, to rotate one of the lock screw elements to permit movement in the direction of thrust applied by said thrust-receiving member.
- 10 11. A thrust-receiving member mounted for movement in the direction of the thrust and a locking screw therefor, in combination with a pilot screw mechanism including an element shiftable to unlock said locking screw and a slip-angle thread for utilizing thrust applied by said thrust-receiving member, to drive said locking support element in either direction at the rate necessary to prevent re-locking.
- 15 12. In releasable thrust mechanism, screw elements mounted for relative rotary screwing movement in thrust relation, but with backlash in the direction of thrust, and coupled thereto, pilot mechanism adapted to relieve thrust on said screw elements and utilize the same to produce relative movement in the direction of the thrust.
- 20 13. Releasable thrust mechanism including continuously meshing screw members which, in the direction of the thrust, are in thrust relation but with clearance affording backlash upon the reversal of thrust and normally locking by frictional engagement when the backlash is taken up in either direction, in combination with pilot mechanism including a pilot screw having the same lead but of smaller pitch diameter so as to permit slip and rotation under thrust, and means for endwise shifting the pilot screw to cause and utilize such rotation to rotate a locking screw element in a direction to relieve pressures on the locking threads and for then automatically screwing said locking thread member at the rate required to maintain such pressure relief, while the parts are moving under load.
- 25 14. A relatively fixed support, a thrust-receiving member mounted for movement with respect thereto, and lock screw elements for locking said member to said support, in combination with pilot screw elements having a slip angle thread, all threads having the same lead and the rotating elements of the lock screw and slip screw being coupled in reciprocal rotary driving relation, in combination with means producing movement of said coupled parts and shifting thrust from and to the slip angle thread for the purpose described.
- 30 15. A relatively fixed support, a thrust receiving member mounted for movement with respect thereto, and lock screw elements for locking said member to said support, in combination with pilot screw elements having a slip angle thread, all threads having the same lead and the rotating elements of the lock screw and slip screw being concentric sleeves splined together in reciprocal rotary driving relation, but with the locking sleeve free for endwise movement to take locking position without stress on the slip sleeve, in combination with means, producing relative movement of the parts which have the reciprocal rotary driving relation and shifting thrust from the locking sleeve to the slip sleeve.
- 35 16. Locking thread elements and slip thread elements, all having the same lead, their rotary thread elements being coaxial and connected in reciprocal rotary driving relation and means whereby the slip thread elements may be relatively moved in position to take load and rotate a locking thread element with the locking threads out of locking contact with each other.
- 40 17. Locking thread elements and separate therefrom slip thread elements, all having the same lead, the rotary thread elements of both being associated in reciprocal rotary driving relation and the slip thread having less backlash than the locking thread, whereby the slip thread elements may be relatively moved in position to take load in both directions and, upon slip movement under load, to rotate a locking thread element with the locking threads out of locking contact with each other.
- 45 18. A relatively fixed support, a thrust-receiving member slidably mounted thereon, a locking screw element on the fixed support parallel with the movement of the thrust-receiving member, a slip thread element on the same support and parallel with said lock thread element, co-operating slip thread and lock thread elements on said thrust-receiving member associated in reciprocal rotary driving relation and both in position to take the thrust of the thrust-receiving element, and the threads of said slip elements and locking elements having the same lead, in combination with selectively operating means for causing either the slip threads or the locking threads to take said thrust.
- 50 19. A relatively fixed support, a thrust-receiving member slidably mounted thereon, a locking screw element on the fixed support parallel with the movement of the thrust-receiving member, a slip thread element on the same support and parallel with said lock screw element, co-operating slip thread and lock thread elements on said thrust-receiving member associated in reciprocal rotary driving relation and both in position to take the thrust of the thrust-receiving element, and the threads of said slip elements and locking

elements having the same lead, in combination with means for moving one of said elements to cause the slip thread to take the thrust and rotate the rotary locking element with its locking threads out of contact with its co-operating locking thread elements.

20. A guide member having a rack, a thrust-receiving member slidably mounted on said guide member for movement parallel with the rack, a locking worm rotatably mounted on the slidable member, a slip thread element rotating therewith, said locking means having its locking threads continuously in mesh with, but loosely fitting between the teeth of the rack, in combination with a pilot screw having a slip thread co-axial with said locking threads and engaging the slip thread element rotating with said locking worm, the slip- and lock-threads having the same lead.

21. A guide member having a rack, a thrust-receiving member slidably mounted on said guide member for movement parallel with the rack, a locking worm rotatably mounted on the slidable member, a slip thread element rotating therewith, said locking means having its locking threads continuously in mesh with, but loosely fitting between the teeth of the rack, in combination with a pilot screw having a slip thread co-axial with said locking threads and engaging the slip thread element rotating with said locking worm, the slip- and lock-threads having the same lead, and means for moving the slip screw endwise to cause it to receive thrust from the thrust-receiving member.

22. The combination specified by claim 20, with means for moving the slip thread endwise to rotate the locking worm thread out of locking engagement with the rack, and to a position where movement of the released thrust receiving member in either direction will cause the rotary slip thread element to rotate and thereby rotate the locking thread element without re-engagement with the rack teeth.

23. A relatively fixed support, a thrust-receiving member mounted for movement with respect thereto, and lock screw elements for locking said member to said support, in combination with pilot screw elements having a slip angle thread, all threads having the same lead; rotating elements of the lock screw and slip screw being concentric sleeves splined together in reciprocal rotary driving relation to permit relative endwise movement and afford independent paths for the end-thrust thereon, one path through the locking sleeve and thread, and another through the slip sleeve and the slip screw; in combination with means for endwise shifting the slip screw to shift thrust from the locking sleeve path to the slip sleeve path to the slip sleeve path.

24. A relatively fixed support, a thrust-receiving member mounted for movement with respect thereto, and lock screw elements

for locking said member to said support, in combination with pilot screw elements having a slip angle thread, all threads having the same lead; rotating elements of the lock screw and slip screw being concentric sleeves splined together in reciprocal rotary driving relation to permit relative endwise movement and afford independent paths for the end-thrust thereon, one path through the locking sleeve and thread, and another through the slip sleeve and the slip screw, and the locking sleeve having more end play than the slip sleeve; in combination with means for endwise shifting the slip screw to shift thrust from the locking sleeve path to the slip sleeve path.

25. A relatively fixed support, a thrust-receiving member mounted for movement with respect thereto, and lock screw elements for locking said member to said support, in combination with pilot screw elements having a slip angle thread, all threads having the same lead; rotating elements of the lock screw and slip screw being concentric sleeves splined together in reciprocal rotary driving relation to permit relative endwise movement and afford independent paths for the end-thrust thereon, one path through the locking sleeve and thread, and another through the slip sleeve and the slip screw, and the locking sleeve having more end play and its threads more back lash than the slip sleeve and thread; in combination with means for endwise shifting the slip screw to shift thrust from the locking sleeve path to the slip sleeve path.

26. A relatively fixed support, a thrust-receiving member mounted for movement with respect thereto, and lock screw elements for locking said member to said support, in combination with pilot screw elements having a slip angle thread, all threads having the same lead; rotating elements of the lock screw and slip screw being concentric sleeves splined together in reciprocal rotary driving relation to permit relative endwise movement and afford independent paths for the end-thrust thereon, one path through the locking sleeve and thread, and another through the slip sleeve and the slip screw, and the locking sleeve having more end play and its threads more backlash than the slip sleeve and thread; in combination with means for endwise shifting the slip screw to shift thrust from the locking sleeve path to the slip sleeve path; together with means for pressing the thrust-receiving member toward the direction of the working thrust.

27. A load receiving screw element threaded to two other screw elements, having the same rate of screw feed but having different pitch diameters so that their stresses and motion producing tendencies with respect to said load are different.

28. A rotary screw element threaded to two

other co-axial screw elements, having the same rate of screw feed but having different pitch diameters such that one is a locking screw thread and the other a slip screw thread, in combination with means for shifting the phase relations of the threads to shift thrust from one thread to the other for the purpose described.

29. In releasable thrust mechanism, screw elements mounted for relative rotary screwing movement in reciprocal thrust relation, but with backlash in the direction of thrust, and pilot mechanism adapted to relieve thrust on said screw elements and utilize the same to produce relative movement in the direction of the thrust, in combination with a shiftable element operable by exterior force in opposition to said thrust and shifting upon reversal of direction of the stress thereon, and means for utilizing such shifting movement to put the pilot mechanism into and out of relation for the above-described operation.

30. In releasable thrust mechanism, screw elements mounted for relative rotary screwing movement in reciprocal thrust relation, but with backlash in the direction of thrust, and pilot mechanism adapted to relieve thrust on said screw elements and utilize the same to produce relative movement in the direction of the thrust, in combination with a shiftable element operable by exterior force in opposition to said thrust and shifting upon reversal of direction of the stress thereon, and means for utilizing such shifting movement to put the pilot mechanism into and out of relation for the above-described operation, together with a spring for the shiftable element normally tending to maintain said element and the pilot mechanism in the above-described thrust-relieving and thrust-utilizing relation.

31. Releasable thrust mechanism including continuously meshing screw members which, in the direction of the thrust, are in thrust relation but with clearance affording backlash upon the reversal of thrust and normally locking by frictional engagement when the backlash is taken up in either direction, in combination with pilot mechanism including a pilot screw having the same lead but of smaller pitch diameter so as to permit slip and rotation under thrust, and means for endwise shifting the pilot screw to cause and utilize such rotation to rotate a locking screw element in a direction to relieve pressures on the locking threads and for then automatically screwing said locking thread member at the rate required to maintain such pressure relief, while the parts are moving under load, a shiftable element operable by exterior force in opposition to the thrust on the releasable mechanism and shifting upon the reversal of the direction of the resultant stress thereon and means for utilizing such shifting to put the pilot mechanism into and out of operative position and a spring for the shiftable ele-

ment normally tending to maintain the same and the pilot mechanism in thrust receiving and thrust utilizing relation.

32. The combination specified by claim 23 wherein the locking sleeve has greater endwise play than the slip-sleeve. 70

33. The combination specified by claim 23, wherein the slip sleeve is endwise supported on ball bearings.

34. A stepless ratchet mechanism including a locking thread element, an endwise movable worm engaging the same and normally locking therewith by friction under thrust, coupled thereto, a pilot mechanism shiftable in a positive manner, to unlock said worm and then to utilize said thrust to rotate said worm. 75

35. A stepless ratchet mechanism including a locking thread element, an endwise movable worm engaging the same and normally locking therewith by friction under thrust, in combination with means for applying thrusts endwise of the worm and means for automatically rotating the worm to positively relieve its locking engagement with said locking thread element when said worm is to move 80

endwise in the direction of thrust.

36. Thrust mechanism including a slip-thread-screw and a rotary nut element adapted for relative slip and rotation under endwise thrust, said screw being of much greater 95 diameter than permissible for the desired slip angle and lead of the thread, and said thread being in the form of a groove having its large-diameter margin cut away so that the threads of the nut element contact only with the desired inner-slip-angle portions of said groove.

37. In releasable thrust mechanism, continuously intermeshed driving and driven thrust transmitting elements, which are normally locked against relative movement in response to thrust, in combination with driving and driven pilot elements, rotatable under thrust, the driving member of the thrust transmitting elements being coupled in reciprocal rotary driving connection to the driven member of the pilot elements, the driven member of the pilot elements, the driven member of the thrust transmitting elements being coupled in reciprocal rotary driving connection to the driving member of the pilot mechanism, one of said couplings being positively variable for the purpose of altering the phase relationship between the thrust transmitting elements and the pilot elements, and means for shifting said variable coupling, whereby the pilot elements are subjected to thrust and move said thrust transmitting elements to a new condition of frictional lock and positively maintain said new condition. 105

38. In releasable thrust mechanism, lock screw elements and slip screw elements, the rotary members of the lock screw and slip screw being coupled in reciprocal rotary driving relation, the non-rotating members of the lock screw and slip screw being coupled in fixed relation, in combination with means for 110

producing relative movement of one of said coupled parts to shift thrust from and to the slip screw for the purpose described.

39. In releasable thrust mechanism, primary and secondary sets of transmission elements, the motion transforming ratios of which are fixed, the primary elements being designed to lock under thrust, the secondary elements being designed for relative rotation under thrust, all the members of both said sets of elements being connected and means for shifting a member whereby the primary elements are subjected to a new condition of lock and the secondary elements are subjected to thrust for positively maintaining said new condition.

Signed at New York, in the county of New York and State of New York, this 28th day of January, A. D. 1922.

20 JULIUS C. HOCHMAN.
